DESIGN FOR HANDLES FOR FIRE-IRONS.

Specification forming part of Design No. 11,257, dated June 24, 1879; application filed May 10, 1879.
[Term of patent 7 years.]

UNITED STATES PATENT OFFICE.

RODOLPHE CHRISTESEN, OF HARTFORD, ASSIGNOR TO THE RUSSELL & ERWIN MANUFACTURING COMPANY, OF NEW BRITAIN, CONN.

DESIGN FOR HANDLES FOR FIRE-IRONS.

Specification forming part of Design No. **11,257**, dated June 24, 1879; application filed May 10, 1879.
[Term of patent 7 years.]

To all whom it may concern:

Be it known that I, RODOLPHE CHRISTESEN, of the city and county of Hartford, and State of Connecticut, have invented a new and useful Design for the Handles for Fire-Irons; and I do hereby declare that the following specification, taken in connection with the accompanying photographic illustration, forming a part of the same, is a full, clear, and exact description thereof.

The novel design, hereinafter described, is adapted to the handles of fire-irons, and consists of the following features: The head A is in the form of an egg, which is ornamented by peripheral beads *a*. This bead surmounts a tapering cylindrical portion, B, which is orna-

mented by peripheral grooves *b*, and also by stems, buds, and flowers *b'*. The portion B surmounts a cylindrical portion, C, which is ornamented by vertical grooves *c* and diagonal grooves *c'*, running in opposite directions, in imitation of marquetry. The lower portion of the cylinder C is contracted and grooved, as at C'.

What I claim, and desire to secure by Letters Patent, is—

The design for a handle for fire-irons, substantially as described and shown.

RODOLPHE CHRISTESEN.
